UNITED STATES PATENT OFFICE.

CLARKE P. POND, OF PHILADELPHIA, PENNSYLVANIA.

WINDOW-OPERATING MECHANISM.

1,151,388.

Specification of Letters Patent. Patented Aug. 24, 1915.

Application filed July 31, 1909. Serial No. 510,672.

To all whom it may concern:

Be it known that I, CLARKE P. POND, a citizen of the United States, residing in Philadelphia, Pennsylvania, have invented 5 certain Improvements in Window-Operating Mechanism, of which the following is a specification.

One object of my invention is to provide simple, substantial, and easily operated 10 mechanism for swinging on their hinges or pivots, the sashes of one or more lines of windows, regardless of the length of the line or of the number of such sashes or lines.

Another object is to provide a novel form 15 of mechanism for transmitting power from an operating cable or chain to the cables, chains, or rods attached to the sash levers; it being desired that such transmitting mechanism shall be capable of moving two 20 operating rods or cables in opposite directions, and where three such rods or cables are used, of moving two of them in one direction and one in an opposite direction.

I further desire to provide novel means 25 for connecting the operating rods with hinged or pivoted sashes regardless of whether such pivots or hinges are horizontal or vertical.

These objects and other advantageous 30 ends I secure as hereinafter set forth, reference being had to the accompanying drawings, in which:—the figure is a perspective view illustrating my invention as employed in operating a horizontal line of sashes so 35 mounted as to swing on vertical pivots.

When it is desired to operate a line of sashes in which the sashes swing on vertical pivots, I provide two operating rods 5 and 5^a both movable in the same direction, and 40 connect to them a third operating rod 6. In this instance each sash has rigidly connected to it two projecting arms 30 each preferably braced by a second arm 31, and connected to the operating rod 5 or 5^a, as the case may 45 be, by a suitable coupling 32.

In order to transmit power from the operating chain 33 to the operating rods, I mount four sprocket wheels, of which two are shown at 26, on the spindle 22 and provide each of them with a sprocket chain 27. The lower ends of all of these sprocket chains are connected by a cross bar 34, which in turn is coupled to the lower operating rod 6, while the upper ends of two of the chains 55 are connected through a cross bar 28 to the operating rod 5^a. The upper ends of the

second pair of chains are connected through a second cross bar 28 to one end of a chain 35 which passes over a suitable pulley 36 and is connected to one end of the operating 60 rod 5. Said pulley 36 is pivotally connected to a wall bracket 37. With this arrangement of parts, the operation of the chain wheel 24 turns the spindle 22 through the worm and worm wheel as before explained, 65 so as to pull the lower operating rod 6, for example, toward the transmission gear. This results in the two operating rods 5 and 5^a being pulled away from said transmission mechanism, so that all of the sashes of the 70 lines are caused to swing on their pivots to an open position;—it being obvious that a reversal of this movement will cause closing of said sashes. In some installations one arm is all that is necessary and but one 75 sprocket wheel and chain are required.

The two rods 5 and 5^a are supported by the sash arms to which they are connected, while for the support of the rods 6, I provide any suitable number of hangers 49 80 rigidly connected to the rod 5^a and provided with a pulley 38 on which said rod 6 rests.

I claim:—

1. The combination of a plurality of sashes to be moved; a plurality of parallel 85 longitudinally extending operating members; means for connecting said members to the sashes; means for moving said members longitudinally, the same consisting of a supporting structure having a spindle; a worm wheel and a plurality of sprocket wheels on said spindle; sprocket chains on said wheels all having one end connected to one of said members and having their opposite ends connected to others of said members respectively; a worm meshing with said worm wheel; and means for actuating said worm. 95

2. The combination, with a plurality of sashes to be moved, of brackets connected to 100 said sashes; sash actuating means in the form of three longitudinally extending members adjacent said sashes; means for connecting two of said members to the brackets of each sash; with means for simultaneously moving said two members in one direction and the third member in an opposite direction. 105

3. The combination of a plurality of sashes; means for operating said sashes consisting of three parallel members extending adjacent said sashes; means for connecting 110

two of said members to each of said sashes; and means for longitudinally moving said two latter members in one direction while moving the third member in an opposite direction.

4. The combination of a plurality of sashes; sash operating means consisting of three parallel members extending adjacent the sashes; means for connecting two of said members to each of said sashes; with means for longitudinally moving said two latter members in one direction while moving the third member in an opposite direction.

tion; the same consisting of a plurality of sprocket chains connecting one of said members with both of the others; sprocket wheels for said chains; and worm gearing for actuating said sprocket wheels.

In testimony whereof, I have signed my name to this specification, in the presence of two subscribing witnesses.

CLARKE P. POND.
